UNITED STATES PATENT OFFICE.

JUDSON D. PERRY, OF DETROIT, MICHIGAN.

MILK-PAIL.

No. 911,262.

Specification of Letters Patent.

Patented Feb. 2, 1909.

Application filed July 1, 1907. Serial No. 381,765.

To all whom it may concern:

Be it known that I, JUDSON D. PERRY, a citizen of the United States of America, residing at Detroit, in the county of Wayne 5 and State of Michigan, have invented certain new and useful Improvements in Milk-Pails, of which the following is a specification, reference being had therein to the accompanying drawings.

10 The invention relates to milk pails of that type in which a portion of the pail forms a seat that can be occupied by the operator.

The invention consists in certain novel features of construction and in the peculiar 15 arrangement and combination of parts as hereinafter set forth.

In the drawings; Figure 1 is a longitudinal section through the pail. Fig. 2 is a perspective view thereof in position for use; 20 and Fig. 3 is a perspective view of the strainer.

A is the body of the pail, which is provided with a relatively large bottom B, and sides tapering toward the upper end. At 25 this upper end is an angling and flaring portion C, the outer rim of which is at an oblique angle to the longitudinal axis of the body portion A.

D are ears secured upon opposite sides of 30 the portion C, adjacent to the center of the pail, and E is a bail, the handle F of which normally rests against the body just inside of the portion C.

G is a strainer which consists of a funnel 35 shaped body arranged to fit within the portion C, with its outer edge adjacent to the rim of said portion. The inner end of this strainer G is contracted to a relatively small area and is covered with a wire mesh fabric, 40 or other suitable straining material H soldered, or otherwise secured to the member G.

45 Adjacent to the bottom of the pail is arranged a supporting standard which, as shown, is formed of a sheet metal member I. This member projects laterally from the bottom B and is flattened at its opposite end to form a supporting base when the pail is turned in a horizontal position. A seat J is formed diametrically opposite the member I, 50 preferably also of sheet metal, and projecting laterally from the body. This portion J, in addition to performing the function of a seat when the pail is in a horizontal position, may also be used as a handle for lifting the 55 bottom of the pail to pour out its contents.

With the construction, as thus far de-

scribed, in use the operator arranges the pail in a horizontal position, as illustrated in Fig. 1, and then sits upon the portion J which, being arranged above the standard portion 60 I, is supported thereby. In this position the body of the pail projects laterally, and the portion C is arranged with its rim in a plane but slightly inclined to the horizontal. Thus the operator can milk directly into the portion G and the strainer H therein, the milk running down the inclined body of the strainer and passing through the straining fabric at its lower end into the body of the pail. Here it will run down the inclined 65 wall of the body, and will accumulate at the base end, gradually rising to fill the entire pail. As the level rises the operator may slightly tilt the body, and in so doing moves the large base end rearwardly of the plane 70 of the support, so as to partially counterbalance the accumulating weight in the forward portion of the pail. Furthermore, by thus tilting the pail, the outer end is raised until finally it reaches the horizontal plane and 75 permits of completely filling the pail.

During the operation of milking, the pail is practically pivoted upon the supporting standard I, so that it is free to turn. Thus, 80 should the cow shift her position, there is 85 no danger of overturning the pail. The supporting base I is, however, preferably elongated laterally to a sufficient distance to permit the operator to shift the pail by alternately inclining the one side or the 90 other, and swinging the free end of the support forward or rearward. At the completion of the operation, the operator, without leaving his seat, can take hold of the handle F and then, as he rises, lift the pail 95 into a vertical position where it is supported upon the bottom B.

It is desirable, when milking, to leave a sufficient quantity of the milk in the strainer to form a froth. This is accomplished by 100 sealing a portion of the straining fabric H, as by filling the same with solder, as indicated at K, thereby forming a pocket or well L in which a small quantity of milk remains constantly during the milking.

105 The construction is such as to permit of easily being cleaned, as the contracted upper end is still of sufficient area to admit of inserting the hand and arm, the strainer being removable and easily cleansed.

110 What I claim as my invention is:

1. A milk pail comprising a tapering

- body having a receiving aperture at its small end and a supporting base at its large end, a bearing formed on one side of said body adjacent to said base constituting a 5 rockable support for the pail when horizontally arranged, and a seat on the opposite side of said pail by which the center of gravity may be shifted to balance the accumulating milk.
- 10 2. A milk pail comprising a tapering body having a receiving aperture at its small end and a supporting base at its large end, a seat and a rockable supporting bear-

ing arranged upon opposite sides of the pail adjacent to said base permitting of the balancing of the pail when horizontally arranged, and a bail at the small end of said pail for lifting the same when arranged in either horizontal or vertical position.

In testimony whereof I affix my signature 20 in presence of two witnesses.

JUDSON D. PERRY
